INTERNAL COMBUSTION ENGINE EXHAUST
SYSTEMEdward V. Rippingille, Detroit, Mich., assignor to
General Motors Corporation, Detroit, Mich., a
corporation of Delaware

Application October 16, 1941, Serial No. 415,164

14 Claims. (Cl. 60—29)

To silence the exhausts of internal combustion engines it has been the general practice to provide a silencer of one kind or another to which the several cylinders of the engine were connected through a manifold. This practice, in the case of engines with cylinders whose exhaust periods overlap, adversely affects the power of the engine because the pressure of and the pulsations in the exhaust gases discharged from one cylinder interferes with the discharge of exhaust gases from the cylinder whose exhaust period its exhaust period overlaps. The effect is, of course, especially pronounced in the cases of two-stroke cycle engines in which the combustion supporting air or combustible mixture is introduced into the cylinders of the engine while their exhaust ports are open.

The undesirable condition under consideration can, of course, be obviated by providing on engines with cylinders whose exhaust periods overlap two or more separate exhaust systems but this, of course, is an expensive practice.

This invention resides in an exhaust system for internal combustion engines which includes a silencer which is so constructed and so connected to a cylinder or cylinders and another cylinder or cylinders whose exhaust period or periods the exhaust period or periods of the former overlaps or overlap that the pressure of and the pulsations in the exhaust gases discharged from the former do not interfere with the discharge of exhaust gases from the latter. Utilization of the invention, consequently, makes it possible to employ on an engine with cylinders whose exhaust periods overlap the exhaust periods of other cylinders a single exhaust system with a single silencer without any adverse effect on the power of the engine.

For a better understanding of the nature and objects of the invention reference is made to the following specification and the accompanying drawing in which are described and illustrated the preferred embodiment of the invention.

In the accompanying drawing.

Figure 1 is a front elevation of an internal combustion engine equipped with exhaust systems in accordance with my invention.

Figure 2 is a side elevation of the engine shown in Figure 1.

Figure 3 is an enlarged lengthwise section through one of the silencers included in the exhaust systems with which the engine shown in Figures 1 and 2 is equipped.

Figure 4 is a section taken on the line 4—4 of Figure 3.

In the drawing the reference character 10 indicates a two-stroke cycle internal combustion engine with four U cylinders 11 disposed radially and equiangularly spaced around the crankshaft.

- 5 10 The cylinders fire successively in the order in which they are arranged around the crankshaft and the exhaust period of each cylinder overlaps that of the cylinder which fires immediately before it.
- 10 To silence the exhaust of the engine 10 there are provided two silencers 12. Each of the silencers includes a shell 13 which is roughly elliptical in cross section and heads 14 which are secured to and close the ends of the shell. Through 15 the shell extend two exhaust gas tubes 15 whose ends are secured in openings in the heads. The axes of the tubes 15 lie in the plane of the major axis of the shell and the tubes are spaced from each other and symmetrically disposed with respect to the minor axis of the shell. The tubes 15 are like the center tube of the silencer shown in Figures 1, 2 and 3 of the Wilson Patent No. 2,332,543, dated October 26, 1943, in that each consists of a tube 16 riddled throughout its length with relatively large (e. g., $\frac{1}{4}$ " diameter circular) perforations 17 snugly telescoped and fixed within a tube 18 riddled throughout its length with relatively small (e. g., $\frac{1}{16}$ " diameter circular) perforations 19. The compartment defined by the shell 13, the heads 14 and the tubes 15 is subdivided lengthwise by partitions 20 which are secured to the shell and through which the tubes extend into chambers 21 which communicate as side branches with the tubes through the perforations 17 and 18.

- 15 The silencers 12 are installed on the engine 10 with one end of each of the exhaust gas tubes 15 of one connected to the exhaust port of one of two of the cylinders 11 which fire in immediate succession and one end of each of the exhaust gas tubes 15 of the other connected to the exhaust port of one of the other two cylinders. To the other end of each of the exhaust gas tubes is connected a tail pipe 22. To connect the silencers to the engine there are provided elbow-like members 23 secured at one end to the cylinders and at the other to imperforate extensions 24 of the exhaust gas tubes. The elbow-like members 23 are gradually enlarged from the points at which they are connected to the extensions 24 to the points at which they are connected to the cylinders, and, in conjunction with domed members 25 which also communicate with the cylinders when their exhaust ports are open, form expansion chambers.

When the engine 10 is operating, exhaust gases pass from the cylinders 11 into the expansion chambers formed by the domed members 25 and the elbow-like members 23 and thence, through the elbow-like members, the exhaust gas tubes 15 of the silencers 12 and the tail pipes 22, to the atmosphere. The chambers 21 and the openings 17 and 19 through which they communicate with the exhaust gas tubes 15, of course, constitute resonators which are preferably so tuned, as set forth in the Wilson Patent No. 2,323,955, dated July 13, 1943, that they will resonate to and thus attenuate sound waves to which the exhaust noise of the engine is attributable.

The exhaust gases discharged from the cylinders 11 which are connected to one of the silencers 12, of course, cannot interfere with the discharge of exhaust gases from the cylinders which are connected to the other of the silencers. The provision in each of the silencers of a separate exhaust gas tube for each of the cylinders to which it is connected effectually minimizes interference by the exhaust gases discharged from one with the discharge of exhaust gases from the other of the cylinders. This because of the resistance offered by the openings 17 and 19 to the transmission of the pressure of and the pulsations in the exhaust gases in one of the tubes 15 to the exhaust gases in the other, both absolutely and relatively to the resistance offered by the tubes and the tail pipes 22 to the transmission thereof to the atmosphere, and the dissipative action of the chambers 21, acting in their capacity of expansion chambers, on the pressure of and pulsations in the exhaust gases. The expansion chambers formed by the domed members 25 and the elbow-like members 23 further minimize interference by the exhaust gases discharged from one of the cylinders with the discharge of exhaust gases from the other of the cylinders connected to the same silencer by the dissipative action of each expansion chamber on the pressure of and pulsations in the exhaust gases which reach it from the cylinder to which it is connected or from the other of the cylinders by way of the chambers 21. The invention, therefore, makes it possible to silence the exhaust of an engine with a plurality of cylinders whose exhaust periods overlap with practically no interference by the exhaust gases discharged from one of the cylinders with the discharge of exhaust gases from the other without a separate exhaust system and silencer for each of the cylinders.

The exhaust periods of the oppositely disposed cylinders of the engine 10 do not overlap. From this and what has been said, it should be clear that the exhaust of the engine 10 or any other engine in which the exhaust period of no cylinder is overlapped by the exhaust period of more than one other cylinder can be silenced with one exhaust system and one silencer like that herein disclosed with practically no interference by the discharge of exhaust gases from any cylinder with the discharge of exhaust gases from any other cylinder by connecting the cylinders in their firing order alternately to one and the other exhaust gas tube of the silencer. This would, of course, in the case of the engine 10 mean connecting both cylinders 11 of each oppositely disposed pair to one of the exhaust gas tubes of the silencer. In the case of the engine shown, this was not done simply because of the impracticability in the installation in which the engine was to be used of the arrangement of exhaust piping which would have been required.

It will, I think, be obvious from what has been said that the exhausts of engines in which the exhaust period of a cylinder is overlapped by the exhaust periods of more than one other cylinder may be silenced with one exhaust system and one silencer with practically no interference by the discharge of exhaust gases from any cylinder with the discharge of exhaust gases from any other cylinder with one exhaust system and one silencer like that herein disclosed but with exhaust gas tubes equal in number to the cylinders by whose exhaust periods the exhaust period of another cylinder is overlapped. It should also, I think, be clear from what has been said that the invention is applicable to the intake as well as the exhaust systems of internal combustion engines.

I claim:

1. In a two stroke cycle internal combustion engine with four cylinders which are disposed radially and spaced equiangularly around the crankshaft and fire successively in the order in which they are arranged around the crankshaft with the exhaust period of each cylinder overlapping the exhaust period of the cylinder which fires immediately before it, a silencer which includes two ducts of which one is connected to the exhaust port of a cylinder and the other to the exhaust port of the cylinder which fires immediately after it, a shell which encircles the ducts and with them defines a compartment, partitions which subdivide the compartment lengthwise into a plurality of chambers of which each communicates with the ducts as a side branch and constitutes an element of a resonator which is so tuned that it resonates to and thus attenuates sound waves which contribute to the exhaust noise of the engine, and a silencer which includes two ducts of which one is connected to the exhaust port of one and the other to the exhaust port of the other of the other two cylinders, a shell which encircles the ducts and with them defines a compartment, partitions which subdivide the compartment lengthwise into a plurality of chambers of which each communicates with the ducts as a side branch and constitutes an element of a resonator which is so tuned that it resonates to and thus attenuates sound waves which contribute to the exhaust noise of the engine, and an expansion chamber through which each of the mentioned ducts is connected to the exhaust port to which it is connected.

2. In an internal combustion engine in which the exhaust period of a later firing cylinder overlaps the exhaust period of an earlier firing cylinder, a silencer which includes a plurality of ducts of which one is connected to the exhaust port of one and another to the exhaust port of the other of the mentioned cylinders but neither is connected to the exhaust port of a cylinder whose exhaust period overlaps the exhaust period of that of the first mentioned cylinders to which it is connected to the same extent as the exhaust period of the earlier firing is overlapped by the exhaust period of the later firing of the first mentioned cylinders, a shell which encircles the ducts and with them defines a compartment, and partitions which subdivide the compartment lengthwise into a plurality of chambers of which each communicates with as a side branch with a plurality of the ducts and constitutes element of a resonator which is so tuned that it resonates to and thus attenuates sound waves which contributed to the exhaust noise of the engine, and an expansion chamber through which each of the

mentioned ducts is connected to the exhaust port to which it is connected.

3. In an internal combustion engine in which the interval the port of a later firing cylinder is open overlaps the interval the corresponding port of an earlier firing cylinder is open, a silencer which includes a plurality of ducts of which one is connected through an expansion chamber to the mentioned port of one and another through an expansion chamber to the mentioned port of the other of the mentioned cylinders but neither is connected to the corresponding port of a cylinder whose open interval overlaps the open interval of that of the first mentioned cylinders to which it is connected to the same extent as the open interval of the earlier firing is overlapped by the open interval of the other later firing of the first mentioned cylinders, and a shell which encircles the ducts and defines with them a compartment which communicates with a plurality of the ducts as a side branch.

4. In an internal combustion engine in which the interval the port of one cylinder is open overlaps the interval the corresponding port of another cylinder is open, a silencer which includes a plurality of ducts of which one is connected through an expansion chamber to the mentioned port of one and another through an expansion chamber to the mentioned port of the other of the mentioned cylinders but neither is connected to the corresponding port of a cylinder whose open interval overlaps the open interval of that of the first mentioned cylinders to which it is connected to the same extent as the open interval of one is overlapped by the open interval of the other of the first mentioned cylinders and a chamber with which a plurality of the ducts communicate between their ends.

5. In a two stroke cycle internal combustion engine with four cylinders which are disposed radially and spaced equiangularly around the crankshaft and fire successively in the order in which they are arranged around the crankshaft with the exhaust period of each cylinder overlapping the exhaust period of the cylinder which fires immediately before it, a silencer which includes two ducts of which one is connected to the exhaust port of a cylinder and the other to the exhaust port of the cylinder which fires immediately after it, a shell which encircles the ducts and with them defines a compartment, partitions which subdivide the compartment lengthwise into a plurality of chambers of which each communicates with the ducts as a side branch and constitutes an element of a resonator which is so tuned that it resonates to and thus attenuates sound waves which contribute to the exhaust noise of the engine and a silencer which includes two ducts of which one is connected to the exhaust port of one and the other to the exhaust port of the other of the other two cylinders, a shell which encircles the ducts and with them defines a compartment, partitions which subdivide the compartment lengthwise into a plurality of chambers of which each communicates with the ducts as a side branch and constitutes an element of a resonator which is so tuned that it resonates to and thus attenuates sound waves which contribute to the exhaust noise of the engine.

6. In an internal combustion engine in which the interval the port of one cylinder is open overlaps the interval the corresponding port of another cylinder is open and the interval the corresponding port of a third cylinder is open

overlaps the interval the corresponding port of a fourth cylinder is open, a silencer which includes two ducts of which one is connected to the mentioned port of one and the other to the mentioned port of the other of the first mentioned cylinders, a chamber with which the ducts communicate between their ends, and a silencer which includes two ducts of which one is connected to the mentioned port of one and the other to the mentioned port of the other of the second mentioned cylinders and a chamber with which the ducts communicate between their ends.

7. In an internal combustion engine in which the exhaust period of a later firing cylinder overlaps the exhaust period of an earlier firing cylinder, a silencer which includes a plurality of ducts of which one is connected to the exhaust port of one and another to the exhaust port of the other of the mentioned cylinders but neither is connected to the exhaust port of a cylinder whose exhaust period overlaps the exhaust period of that of the first mentioned cylinders to which it is connected to the same extent as the exhaust period of the earlier firing is overlapped by the exhaust period of the later firing of the first mentioned cylinders, a shell which encircles the ducts and with them defines a compartment, and partitions which subdivide the compartment lengthwise into a plurality of chambers of which each communicates as a side branch and with a plurality of ducts constitutes an element of a resonator which is so tuned that it resonates to and thus attenuates sound waves which contribute to the exhaust noise of the engine.

8. In an internal combustion engine in which the exhaust period of a later firing cylinder overlaps the exhaust period of an earlier firing cylinder, a silencer which includes a plurality of ducts of which one is connected to the exhaust port of one and another to the exhaust port of the other of the mentioned cylinders but neither is connected to the exhaust port of a cylinder whose exhaust period overlaps the exhaust period of that of the first mentioned cylinders to which it is connected to the same extent as the exhaust period of one is overlapped by the exhaust period of the other of the first mentioned cylinders, and a shell which encircles the ducts and with them defines a compartment which communicates as a side branch with a plurality of the ducts and is so tuned that it resonates to and thus attenuates sound waves which contribute to the exhaust noise of the engine.

9. In an internal combustion engine in which the exhaust period of one cylinder overlaps the exhaust period of another cylinder, a silencer which includes a plurality of ducts of which one is connected to the exhaust port of one and another to the exhaust port of the other of the mentioned cylinders but neither is connected to the exhaust port of a cylinder whose exhaust period overlaps the exhaust period of that of the first mentioned cylinders to which it is connected to the same extent as the exhaust period of one is overlapped by the exhaust period of the other of the first mentioned cylinders, and a chamber with which a plurality of the ducts communicate between their ends.

10. In an internal combustion engine in which the interval the port of a later firing cylinder is open overlaps the interval the corresponding port of an earlier firing cylinder is open, a silencer which includes a plurality of ducts of which one is connected to the mentioned port of one and

another to the mentioned port of the other of the mentioned cylinders but neither is connected to the corresponding port of a cylinder whose open interval overlaps the open interval of that of the first mentioned cylinders to which it is connected to the same extent as the open interval of the earlier firing is overlapped by the open interval of the other later firing of the first mentioned cylinders, and a shell which encircles the ducts and defines with them a compartment which communicates with a plurality of the ducts as a side branch.

11. In an internal combustion engine in which the interval the port of one cylinder is open overlaps the interval the corresponding port of another cylinder is open, a silencer which includes a plurality of ducts of which one is connected to the mentioned port of one and another to the mentioned port of the other of the mentioned cylinders but neither is connected to the corresponding port of a cylinder whose open interval overlaps the open interval of that of the first mentioned cylinders to which it is connected to the same extent as the open interval of one is overlapped by the open interval of the other of the first mentioned cylinders, and a plurality of chambers with each of which a plurality of ducts communicate between their ends.

12. In an internal combustion engine in which the interval the port of one cylinder is open overlaps the interval the corresponding port of another cylinder is open, a silencer which includes a plurality of ducts of which one is connected to the mentioned port of one and another to the mentioned port of the other of the mentioned cylinders but neither is connected to the corresponding port of a cylinder whose open interval overlaps the open interval of that of the first mentioned cylinders to which it is connected to the same extent as the open interval of one is overlapped by the open interval of the other of

the first mentioned cylinders, and a shell which encircles the ducts and defines with them a compartment which communicates with a plurality of the ducts as a side branch.

13. In an internal combustion engine in which the interval the port of one cylinder is open overlaps the interval the corresponding port of another cylinder is open, a silencer which includes a plurality of ducts of which one is connected to the mentioned port of one and another to the mentioned port of the other of the mentioned cylinders but neither is connected to the corresponding port of a cylinder whose open interval overlaps the open interval of that of the first mentioned cylinders to which it is connected to the same extent as the open interval of one is overlapped by the open interval of the other of the first mentioned cylinders, and a chamber with which a plurality of the ducts communicate between their ends.

14. In an internal combustion engine in which the interval the port of one cylinder is open overlaps the interval the corresponding port of another cylinder is open, a silencer which includes a plurality of ducts of which one is connected to the mentioned port of one and the other to the mentioned port of the other of the mentioned cylinders but neither is connected to the corresponding port of a cylinder whose open interval overlaps the open interval of that of the first mentioned cylinders to which it is connected to the same extent as the open interval of one is overlapped by the open interval of the other of the first mentioned cylinders, and a chamber which communicates as a side branch with a plurality of the ducts and is so tuned that it resonates to and thus attenuates sound waves which contribute to the noise of the engine which issues from the mentioned ports.
